UNITED STATES PATENT OFFICE.

CARL WINKLER, OF BERNE, SWITZERLAND.

MOLD FOR CASTING STEREOTYPE PLATES.

Application filed March 21, 1925. Serial No. 17,372.

To all whom it may concern:

Be it known that I, CARL WINKLER, a citizen of the Swiss Republic, residing at Berne, in the Swiss Republic, have invented new and useful Improvements in Molds for Casting Stereotype Plates, of which the following is a specification.

The invention relates to a mold for casting stereotype plates of the kind in which the clamp holding one edge of the matrix is coupled with the side mold bars, and, by these, with the foot bar, and, in opening the mold, is mechanically moved to strip the matrix off the plate.

The characteristic feature of the invention consists in providing the matrix clamp, which is hinged to the mold, with a handle projecting forwards, by means of which the matrix clamp, together with the side, and foot bars, can be tilted by hand, so that, previous to casting a plate, it can be tested whether the matrix has the right position in the mold.

In the drawing illustrating the invention by way of example.

Fig. 1 is a perspective view of the mold in the casting position, and

Fig. 2 a similar view of the mold with the matrix clamp, side and foot bars partly raised.

The matrix clamp *a* turns about the axis *b* and holds one edge of the matrix. To the

side bars *d* the matrix clamp *a* is connected by pins fastened to said bars, which pins project into the guides *e* on the matrix clamp, so that by raising the inner edge of this clamp from the position in Fig. 1 into that shown in Fig. 2, which is done by pressing down the handle *f*, the bars *d* are also raised. At the same time the foot bar *g* is turned up a little by the side bars. Consequently, the matrix *c* is free under the side bars *d* and the foot bar *g*, so that it can take part in the small movement of the matrix clamp. By raising and lowering the clamp it can therefore be ascertained whether the matrix is properly seated in the mold.

What I claim and desire to secure by Letters Patent of the United States is:

A mold for casting stereotype plates comprising in combination a matrix clamp for holding one edge of the matrix, side bars connected to said clamp, a foot bar connected to said side bars, and a handle on said matrix clamp adapted to tilt said clamp side bars and foot bar, substantially as set forth.

In testimony whereof I have signed my name to this specification in the presence of two subscribing witnesses.

CARL WINKLER.
